US00D972627S

(12) **United States Design Patent** (10) **Patent No.:** **US D972,627 S**
(45) **Date of Patent:** **** Dec. 13, 2022**

(54) **EYEGLASSES**

(71) Applicant: **Oakley, Inc.**, Foothill Ranch, CA (US)

(72) Inventors: **Joon H. Kim**, Hacienda Heights, CA (US); **Nicolas Adolfo Garfias**, Long Beach, CA (US)

(73) Assignee: **Oakley, Inc.**, Foothill Ranch (CA)

(**) Term: **15 Years**

(21) Appl. No.: **29/753,389**

(22) Filed: **Sep. 30, 2020**

(51) LOC (13) Cl. **16-06**

(52) U.S. Cl.

USPC **D16/335**

(57) **CLAIM**

The ornamental design for eyeglasses, as shown and described.

DESCRIPTION

FIG. 1 is a top front perspective view of eyeglasses showing the claimed design;

FIG. 2 is a front view thereof;

FIG. 3 is a rear view thereof;

FIG. 4 is a right side view thereof, the left side view being a mirror image thereof;

FIG. 5 is a top view thereof; and,

FIG. 6 is a bottom view thereof.

The dashed broken lines in the figures show portions of the eyeglasses that form no part of the claimed design.

The dot-dash broken lines in the figures show boundaries that form no part of the claimed design.

1 Claim, 5 Drawing Sheets
